UNITED STATES PATENT OFFICE.

JOHN M. TERZICH, OF AMADOR CITY, CALIFORNIA.

ELECTRIC SWITCH.

1,238,597.

Specification of Letters Patent. Patented Aug. 28, 1917.

Application filed May 26, 1916. Serial No. 100,136.

To all whom it may concern:

Be it known that I, JOHN M. TERZICH, a citizen of the United States, residing at Amador City, in the county of Amador and 5 State of California, have invented new and useful Improvements in Electric Switches, of which the following is a specification.

This invention relates to improvements in electric switches.

10 One of the objects of the invention is to provide a switch having a more effective means for establishing good connection between the blade and blade-mounting.

Another object is to provide a switch 15 wherein the blade will be securely retained in the open position until manually or otherwise released.

With these and other objects in view the invention will be better understood from 20 the following detailed description taken in connection with the accompanying drawings, wherein

Figure 1 is a side elevation of the switch in the open position.

25 Fig. 2 is a side elevation of the switch in the closed position.

Fig. 3 is a perspective view of the switch arm and mounting.

Referring to the drawings the numeral 7 30 designates a base upon which is mounted a pair of contacts 8 and 9, the former supporting a pivot bolt 10, the latter bifurcated as indicated so as to engage the wedge shaped ends 12 of the switch arm 13 that has its 35 other end rotatably connected to the bolt 10.

Upon the base 7 I provide a finger 14 normally holding the blade 13 in open position and adapted to be thrown to a position to allow the switch blade to move to closed position upon actuation of any suitable operating device which may be arranged to operate the finger. To accomplish this result the finger 14 is pivotally mounted within the bearing 15 carried by the base 7. The finger 45 is so disposed that when in normal position it lies in alinement with the path of movement of the arm 13 but sliding movement of the finger to one side of this position will allow the arm 13 to further move the 50 finger until engagement is had between the contacts and arm. It will be seen from the drawings that in the normal position the finger 14 rests in a curved portion of the arm 13 whereby accidental displacement is rendered less likely to occur.

In the form of my invention shown in Fig. 1 gravity is relied on to bring about engagement between the switch arm and the contact, whereas in Figs. 2 and 3 I have illustrated the contact 20 so constructed as 60 to pivotally support the switch arm 21 and at the same time to yieldably force the same toward closing position. To accomplish this action the contact 20 is provided with resilient extremities 21' and 22 disposed on 65 opposite sides of the switch arm and continuously bearing against a pin 23 that passes through the switch arm. By this construction the switch arm is made to snap into the contact so as to insure a good electrical connection when the finger is moved to an inoperative position while the rubbing contact of the resilient extensions 21' and 22 against the pin 23 insures good electrical connection.

70 It is to be understood that while all of the several features of my improved device have special coöperation with one another and together constitute a particularly effective mechanism for the purpose in view, certain 75 of these features may be applied in other relations, and I therefore desire to cover the combination present in the several parts of my improved apparatus whether employed in the general organization shown or else- 80 where.

Having described my invention, what I claim is:

1. A switch comprising an arm, a pivot 85 for said arm and a support for the pivot; 90 resilient extensions of said support and projecting portions of said arm adapted to be engaged by said extensions; contact jaws adapted to be engaged by said arm, a pivoted finger adapted to prevent movement of 95 said arm toward said contact jaws in one position and to permit such movement in the other position.

2. A switch comprising an arm, a pivot 100 for said arm and a support for the pivot; 105 resilient extensions of said support and projecting portions of said arm adapted to be engaged by said extensions; contact jaws adapted to be engaged by said arm, a pivoted finger adapted to prevent movement of 110 said arm toward said contact jaws in one position and to permit such movement in the other position, said finger in alinement with the path of movement of said arm in the first position and adapted to be forced

by said arm to said second position upon being displaced from alinement with said arm.

3. A switch comprising an arm, a pivot for said arm and a support for the pivot; resilient extensions of said support and projecting portions of said arm adapted to be engaged by said extensions; contact jaws adapted to be engaged by said arm, a pivoted finger adapted to prevent movement of said arm toward said contact jaws in one position and to permit such movement in the other position, said finger in alinement with the path of movement of said arm in the first position, said arm formed with a curved portion adapted to be engaged by said finger in the first mentioned position, whereby said arm is raised against the pressure of said resilient extensions when said finger is displaced from alinement with the

path of movement of the arm to permit the 20 arm to move to the closed position.

4. A switch comprising an arm, a pivot for said arm and a support for the pivot; resilient extensions of said support and projecting portions of said arm adapted to be 25 engaged by said extensions, said extensions constituting a spring means for said arm, said extensions constituting an integral part of said support, and said extensions adapted for rubbing contact with said projecting 30 portions of said arm, whereby good electrical connection is maintained between said arm and said support.

In testimony whereof I affix my signature.
JOHN M. TERZICH.

Attest:

EARL E. PARLIN,
V. B. Fox.
